(57) **CLAIM**

The ornamental design for a feed cartridge for three-dimensional object material, as shown and described.

DESCRIPTION

FIG. 1 is a reduced front perspective view of a feed cartridge for three-dimensional object material showing our new design;

FIG. 2 is a top plan view thereof;

FIG. 3 is a side elevational view thereof; and,

FIG. 4 is an enlarged partial view of the top portion of FIG. 3.

The broken lines are for purposes of illustration only and form no part of the claimed design.
